JOSIAH Y. HOAGLAND, OF AUBURN, NEW YORK.

Letters Patent No. 75,633, dated March 17, 1868.

IMPROVEMENT IN MACHINE FOR GRINDING HARVESTER-KNIVES.

The Schedule referred to in these Letters Patent and making part of the same.

TO ALL WHOM IT MAY CONCERN:

Be it known that I, JOSIAH Y. HOAGLAND, of the city of Auburn, New York, have invented a new and useful Machine for Grinding Harvester-Knives; and I hereby declare that the following is a full, clear, and exact description thereof, and of the operation thereof, reference being had to the accompanying drawings, in which—

Figure 1 is a view of the whole machine, and the grindstone with which it is connected when in operation.

Figure 2 is a side view of the whole machine, connected with a grindstone, in operation.

Figure 3 is a rear view of my attachment, without the holder, as it sets upon and is attached to the upper portion of the frame of the grindstone.

Figure 4 is a front view of the metal holder, with the cutter-bar and cutters therein.

Figure 5 is the end view of the holder.

A represents the frame which supports the grindstone. B represents the grindstone. C represents the grooved platform, which supports the standard to which the holder is affixed. D represents the bottom-piece, upon which the standard is cast, and which slides upon the platform C. E represents the base of the standard. F represents the centre-piece of the standard. G represents the upper portion of the standard. H represents the upper part of the holder. I represents the under part of the holder, or that part next the grindstone. J represents the lever, by which the cutter is pressed against the stone when being ground. a represents a gutta-percha spring, which causes the machine or implement to recede from the stone when the lever is loosened. b represents the chain, attached to the front or inner end of the machine. c represents the treadle, by which the chain b is moved.

In constructing my machine, I first make the platform C of cast iron, and three inches wide by four inches in length. A groove is cast upon the inside of each of the sides thereof, in which the piece D, upon which the standard is cast, will play. I then affix this platform rigidly upon one end of the frame which supports the grindstone.

I then make the bottom-piece D and the base-piece E of the standard, the whole being cast in one piece, and said bottom-piece of such dimensions as to fit into the grooves of the platform C. The base, E, I make about one and one-half inch in diameter, and about one inch in height. In this base-piece I cast or drill a hole to receive and hold the stud of centre-piece F of the standard.

I then make the centre-piece F of said standard of cast iron, and of the same diameter as the said base-piece, and cast thereon a stud to fit the hole in the base-piece E. I make this piece about two and one-fourth inches in length, of the same diameter as the other parts of the standard. The top thereof is cast with a shoulder, bevelled both at the top and sides, and the upper part of a curved form, so that the upper portion of the said standard may play towards or from the grindstone.

I then make the upper portion G of said standard, the under part thereof in such form as to fit snugly upon and to the upper part of the centre-piece F, and of the same diameter, and about three inches in length. The face of this upper portion G is made flat, against which the holder is drawn and held tightly.

I then make the upper or outer part of the holder H of cast iron, with a bevelled rabbet, to form, with the metal piece I, a groove to receive the back of the cutter-bar. I make this holder about fifteen inches in length.

I then make the metal piece I, which is to form the under side of the holder, which I make of sheet iron, and about twelve inches in length, and about one inch in width.

Having thus described the construction of my machine, I will describe the manner of connecting the several parts, and the mode of operation when in use.

I first affix the grooved platform C rigidly upon one end of the frame of any ordinary grindstone. I then slide the bottom-piece D, with its base-piece E, thereto attached, thereon. I then connect the centre-piece F with the base-piece E, and attach thereto the upper portion G by a bolt passing through them both. I then affix the holder H to the face of this upper portion by a screw-bolt. I then place the cutter-bar, with the knives or cutters thereto attached, in the groove of said holder, and fasten the same by nuts and screws, and the machine is ready to be operated.

It will be perceived that the centre-piece F of the standard may be turned around to any extent, and that the upper piece G may be moved backward or forward, so that the knives or sections may be inclined toward the stone at a greater or less angle, and the holder being attached to the face of the upper portion of the standard G by means of the screw-bolt passing through the centre, thereby enables the operator to turn said holder with the cutter-bars thereto attached, which forms, when thus arranged and combined, a universal joint, and enables the operator to bring the knives to the stone at any angle desired, and thereby enables him to grind the knife to any desired bevel.

In order to press the knives against the stone as desired, I place a spring of gutta percha, a, around the standard, having pieces at the two outer corners of the platform to receive and hold it, and a projection upon the inner end of the base-piece E to receive it, so that said spring will form nearly a triangle. To the inner end of said base-piece I attach one end of a light chain, b, and affix the other end to the lever, J. When the lever is pressed backward, the base-piece, with all that is supported thereby, will be drawn to the face of the stone, and the pressure upon the lever must necessarily control the pressure of the knives upon the stone. When the pressure of the lever J is removed the spring a will necessarily draw the bottom-piece, with all supported thereby, from the stone, and the operator can then readily move the cutter-bar laterally, so as to present a different knife or section to the stone to be ground, or the chain may be attached to the treadle, and the treadle worked by the foot of the operator if desired, or by reversing the bottom-piece D, with the base-piece E thereto, attached thereon, and the gutta-percha spring reversed on corners of platform C, makes my machine a self-presser upon the grindstone.

Having thus fully described the construction of the component parts of my machine, their arrangements and connections, and the mode of operation thereof, what I claim as my invention, and desire to secure by Letters Patent, is—

1. Affixing the machine for grinding the knives or sections of a harvester upon the frame of any ordinary grindstone, so as to bring the said knives or sections to the face of the stone to be ground, substantially as above described.
2. The grooved platform C, in combination with the bottom-piece D and the standard E F G, substantially as and for the purpose above described.
3. The combination of the three parts E, F, and G, of the standard, constructed and arranged substantially as and for the purpose described.
4. The combination of the three parts E, F, and G, with the holder H I, so as to form a universal joint, substantially as and for the purpose above described.
5. Attaching a spring to the bottom-piece D, so as to draw the cutter-bar from the stone, substantially as described.
6. The combination of the spring a, the chain b, and the lever J, substantially as and for the purpose described.
7. The combination of the spring a, the chain b, and the treadle c, substantially as and for the purpose described.
8. Attaching a spring to the bottom-piece D, so as to draw the cutter-bar to the stone, making thereby an automatic presser, substantially as and for the purpose described.

Auburn, January 6, 1868.

JOSIAH Y. HOAGLAND.
